(57) **CLAIM**

The ornamental design for a golf ball, as shown and described.

DESCRIPTION

FIG. 1 is a front view of an example golf ball incorporating a pattern of 300 dimples;

FIG. 2 is a top view, as seen when FIG. 1 is rotated 70° forward on the horizontal axis; and,

FIG. 3 is an upper side view, as seen when FIG. 1 is rotated 90° about its vertical axis, and 20° backward on its horizontal axis.
